UNITED STATES PATENT OFFICE

2,576,131

BUFFING APPARATUS

George Albert Lyon, Detroit, Mich.

Application February 15, 1949, Serial No. 76,479

10 Claims. (Cl. 51—263)

1

The present invention relates to an apparatus for carrying out buffing or polishing operations.

In usual polishing operations, wherein rotating buffing wheels are brought into contact with different parts of the work as the same is rotated or moved through a predetermined path, a buffing compound is manually applied to the surface of the buffing wheel from time to time by the operator. Normally, this is accomplished by holding a block or rod of buffing compound against the periphery of the buffing wheel. Such manual treatment of the buffing wheel with the buffing compound has many inherent disadvantages. For one, it is dangerous to the operator because of the possibility of the operator's arm being accidentally thrown against a moving part of the mechanism or against the moving workpiece.

Further, this method of applying a buffing compound is extremely wasteful as there is normally no means other than the operator's skill for gauging the amount of buffing compound which is being applied to the wheel. A definite minimum amount of buffing compound is necessary to adequately coat or impregnate the surface of the wheel, so that the buffing wheel will not be burned during the buffing operation. Hence, it is normal practice to provide an excess of the buffing compound for coating the surface of the wheel. Since buffing compounds are relatively expensive, this procedure is quite wasteful and represents a considerable part of the cost of any buffing operation.

Further, there is no assurance when a buffing compound is applied in this manner, that an even coating of the compound will be applied to the surface of the buffing wheel.

One of the main features of the present invention is that it provides a system whereby a buffing wheel is alternately contacted by a workpiece and by a block of buffing compound, each operation being carried out for predetermined periods of time and in such a manner that the buffing wheel always takes the same amount of buffing compound during each dressing operation, and always maintains the same alignment with the workpiece during the buffing operation.

In one preferred embodiment of the present invention, there is provided a tiltable housing which carries a buffing wheel thereon, the buffing of the workpiece being done at one end of the tilting movement, and the finishing application to the wheel of the buffing compound being carried out at the other end of such movement. Means are also provided whereby the tilting movement of the buffing wheel housing automatically indexes the

2

buffing compound toward the buffing wheel a predetermined amount to compensate for the amount of compound removed during the finishing operation. In addition, means are provided for extending the arc subtended by the tilting movement to compensate for the wear on the surface of the buffing wheel during the polishing operation. The aforementioned means are integrated into the assembly so that both functions are performed automatically.

As another feature of the present invention, there is provided a new type of holder for the buffing compound designed in a manner such that there is a minimum of wastage of the buffing compound held therein.

It is, therefore, an object of the present invention to provide an apparatus for performing a polishing operation in which the loss of buffing compound is held to a minimum.

20 It is a further object of the invention to provide an apparatus for polishing operations with means therein for controlling the amount of buffing compound to be applied to the wheel.

It is a still further object of the invention to 25 provide an apparatus for polishing and buffing operations in which the buffing compound is automatically advanced a predetermined amount after each buffing operation, so that the buffing wheel takes off the same amount of compound during each operation.

30 Still another object of the present invention is to provide an apparatus for buffing assemblies which compensates for the wear of the surface of the buffing wheel itself during the buffing operation, and does so in an automatic manner.

35 A further object of the present invention is to provide an apparatus for applying a buffing compound to buffing wheels without the hazards previously connected with this operation.

40 Other objects and features of the present invention will become apparent from the following description of the attached sheet of drawings, in which:

45 Figure 1 is an end elevational view of the assembly embodying my invention;

Figure 2 is a side elevational view of the apparatus.

Figure 3 is a top plan view of the apparatus showing the buffing wheel in contact with a workpiece;

50 Figure 4 is an enlarged fragmentary sectional view of the indexing mechanism of the present invention taken along the line IV—IV of Figure 2;

55 Figure 5 is an enlarged, fragmentary, side

elevational view of the indexing mechanism mentioned above with parts in section;

Figure 6 is an enlarged sectional view taken substantially along the line VI—VI of Figure 1, showing the holder for the buffing compound with a block of compound mounted therein;

Figure 7 is a fragmentary end elevational view, similar to Figure 1, illustrating the working position of the buffing compound holder in contact with the surface of a buffing wheel;

Figure 8 is a view similar to Figure 7, showing the buffing wheel in contact with the buffing compound after a considerable portion of the compound has been used;

Figure 9 is a fragmentary, enlarged end elevational view of the holder containing a block of buffing compound; and

Figure 10 is a perspective view of the holder with the block of buffing compound removed.

As shown on the drawings:

Reference numeral 10 denotes in general a housing containing a pair of angularly disposed yokes 11 and 12 (Figures 1 and 2) secured together at their uppermost portions by means of bolts 13 and 14 which pass through flanges 15 and 16 of the yoke 11 and corresponding flanges on the yoke 12. The yokes 11 and 12 are mounted upon a base frame 17, from which depend bearing housings 18 and 19. The housings 18 and 19 receive a shaft 20 which is stationarily held at its ends in supporting blocks 21 and 22 projecting from the base 23 of the assembly.

Disposed within the housing 10 and within the yokes 11 and 12, is a supporting table 24 mounted from the base frame 17. Said table 24 is apertured at its corners to receive bolts 25, which are threaded through the base 17 of the housing 10 and held therein by means of nuts 28.

A strap 31 is anchored to said supporting table 24 and serves to retain thereon a motor 32 having a drive shaft 33. Rotational torque produced of the motor 32 is supplied from the drive shaft 33 by means of V-belts 34 to a spindle 35. The spindle 35 is journaled for rotation within a housing 36 carried by the yokes 11 and 12 and drives a conventional buffing wheel 37.

The housing 10 is capable of rocking movement about the shaft 20 by means of the double acting cylinder 38 (Figures 1 and 2). The cylinder 38 may also be used to index the various workpieces into alignment with the surface of the buffing wheel 37. The operation of the cylinder 38 is conventional, as will be readily appreciated by those skilled in the art.

At one end of its rocking movement, as illustrated by the dotted lines of Figure 1, the periphery of the buffing wheel 37 is brought into contact with a solid block of buffing compound 39 held within a holder 40, the details of which will be hereinafter described. The holder 40 (Figures 2, 3, 6 and 7) is held within an adapter 41 having upturned flange portions 42 and 43. The adapter 41 is fixedly secured to an arm 44. The arm 44 is mounted by means of a sleeve 45 for pivotal movement about the shaft 20.

To provide indexing of the assembly to compensate for both the wear on the buffing wheel and the removal of buffing compound from the block 39 during each cycle of operation, a novel indexing assembly is herein provided. The indexing assembly (Figures 1, 2, 4 and 5) consists of a horizontal table 46 supported by means of upright legs 47 on a base 48. The base 48 is in turn rigidly secured to supporting means such as channel beams 49.

Attached to the table 46 are a pair of bearing members 50 and 51 in which are journaled the smooth cylindrical end portions of a threaded lead shaft 52. The shaft 52 is threaded, as at 53, along the major portion thereof, and also has a reduced unthreaded portion 54. Rotation of the shaft 52 may be effected by operation of a ratchet wheel 55 keyed to one end thereof or by means of a manually operable wheel 56 located at the opposite end thereof. As the shaft 52 is rotated, the rotation causes a movement of a sliding block 57 which is in threaded engagement with the shaft 52 and slideable along the table 46. Such movement of the block 57 causes a lever 58, attached to the block, to pivot the arm 44 about the axis of the shaft 20 and move the holder 40 and the buffing compound 39 a predetermined amount toward the surface of the buffing wheel 37. As will be hereinafter described, the assembly is calibrated so that the eventual movement of the block of buffing compound 39 compensates exactly for the amount of surface worn from the buffing compound 39 during its contact with the buffing wheel 37.

To impart the desired amount of rotation to the shaft 52 and thereby move the block of buffing compound 39 the correct amount, there is provided an assembly (Figures 4 and 5) which includes a sleeve 59 secured to the table 46, a slide 60 slidable within the sleeve 59, and a pawl 61 pivoted to the slide 60 by means of a pin 62. The lowermost end of the slide 60 is formed into a bifurcated portion having a roller 63 rotatably held therein by means of a shaft 64. One end of the shaft 64 is rotatably held within a slot 65 of a bracket 66. This bracket 66 is fixedly secured to an arm 67. The arm 67 is rigidly secured, as by welding or the like, to a second arm 69 carried by the tilting housing 10.

The operation of the indexing device is as follows:

As the tiltable housing 10 carrying the buffing wheel 37 is tilted by the reciprocating action of the cylinder 38 to effect contact between the periphery of the buffing wheel 37 and the block of buffing compound 39 as shown by the dotted line portion of Figure 1, the arm 69 swings downwardly and carries with it the arm 67 and the slide 60. The horizontal component of such motion is compensated for by movement of the roller 63 in the slot 65, so that the slide 60 moves only in a downward direction. As the slide 60 moves downwardly, the pawl 61 drops to a position below the next succeeding tooth on the ratchet wheel 55 against the bias afforded by the spring 70. As is best shown in Figures 2, 3, and 5, the pawl 61 is set back into a recess in the slide 60, the movement of the pawl 61 being limited by inclined faces 60a and 60b formed on the surface of the slide 60. With reference to Figure 5, the downward movement of the slide 60 will carry the pawl 61 from its position adjacent the tooth A of the ratchet wheel 55 to a position below the next tooth B. When the tiltable housing 10 is tilted in the opposite direction, the arms 69 and 67 force the slide 60 upwardly within the sleeve 59, and the pawl 61 will contact the base of the tooth B and rotate it into the position formerly assumed by the tooth A. It will be evident that the pawl 61 is free to pivot in one direction only, that is, during the downward stroke of the slide 60, since it is held against pivoting in the other direction by means of the faces 60c and 60d formed in the face of the slide 60. This rotation of the ratchet wheel 55 is transmitted to the shaft

52 by virtue of the direct connection between the two elements, and causes the sliding block 57 to move forwardly toward the ratchet wheel 55. This movement is imparted to the buffing compound holder 40 and the buffing compound 39 held therein by means of the lever 58 which is pivotally mounted to the sliding block 57 on one surface thereof by means of a pin 71 and to the arm 44 by means of a pin 72 (Figure 2). The pitch of the threaded portion 53 is such that the resultant movement imparted to the block of buffing compound 39 in the direction of the periphery of the buffing wheel 37 corresponds to the amount of buffing compound to be applied to the surface of the wheel during each dressing operation. Normally, this will be on the order of .005 inch.

Thus, upon each cycle of tilting movement by the housing 10, the buffing compound 39 is advanced the same predetermined amount toward the surface of the buffing wheel 37. It will be noted that the buffing compound is automatically applied to the surface of the buff wheel at a point remote from the point where the buffing wheel contacts the workpiece.

The time of contact between the buffing wheel 38 and a fixed workpiece W, shown in Figure 3, is determined by timing means (not shown) which cooperate with the cylinder 38 so that the assembly is automatically moved between the position where the wheel 37 contacts the workpiece W and the position against the surface of the buffing compound 39 after a predetermined buffing time has elapsed. The position of any workpiece W is fixed with respect to the wheel 37, so that means must be provided to compensate for the wear of the surface of the wheel 37 during each buffing operation.

The indexing mechanism which serves to advance the buffing compound toward the buffing wheel also functions to compensate for the wear on the buffing wheel during each buffing operation. In specific instances, this wear will amount to approximately .00075 inch for every operation. To make this compensation, the assembly is provided with means for advancing the tilting arc of the housing and the buffing wheel so that the wheel and the workpiece are brought into the correct pressure relationship for each buffing operation.

To accomplish this purpose, there is provided a flanged plate 73 which is affixed to the sliding block 57 by means of bolts 74 and 75. The flanged plate 73 is slideable along ways 76 and 77 formed at the base of the horizontal table 46. The base of the sliding plate 73 slopes downwardly from the horizontal, and carries a bar 78 secured in a channel in the under surface of said plate 73. The limit to which the buffing wheel assembly can be tilted in the direction of the workpiece is determined by the point of contact between the bar 78 and an adjusting screw 79, which is threaded into a sleeve 80 held by the aforementioned arm 67. It will be noted that as the sliding block 57 moves horizontally along the horizontal table 46, the plate 73 and bar 78 will be advanced horizontally within the ways 76 and 77. Thus, the adjusting screw 79 will contact a different point along the inclined base of the bar 78 during each movement of the buffing wheel 37 toward the workpiece. The inclination of the bar 78 will determine the amount that the tilting movement of the buffing wheel will be displaced during each cycle. By the proper adjustment of the inclination, the tilting arc can be extended by incre-

ments exactly equal to the radial shrinkage of the buffing wheel due to wear in its contact with a workpiece.

As another feature of the present invention, I have herein provided a novel type of holder for the buffing compound which provides for maximum utilization of the rather expensive compound. The holder 40 comprises a base 81 (Figures 6 and 10) having a notch 82 along one edge thereof, and to which are secured a pair of upstanding wall portions 83 and 84 having upper outturned flanges 85 and 86. The spacing between the walls 83 and 84 is slightly larger than the thickness of the buffing wheel 31, so that the buffing wheel 37 is movable within the holder assembly. The rear of the holder assembly is provided with an inclined backing member 87 having holes 97 therein to allow the buffing compound to become anchored within the holder as a result of the pressure exerted on the compound by the contact with the buffing wheel. Extending from the backing member 87 to the base 81 is an arcuate backing piece 88 which has a radius of curvature corresponding approximately to the mean working radius of the buffing wheel 37.

The assembly may be filled by moulding a buffing compound 39 within the holder 40 and may be repeatedly reused.

The assembly shown in Figure 10 is inserted within a channel defined by the upturned flanges 42 and 43 of the arm 44 by means of two upstanding plates 89 and 90 (Figure 6) having a series of longitudinally extending notched channels 91. The plates 89 and 90 are provided with inclined sidewall portions 92 (Figure 9) which determine the extent to which the holder assembly can be inserted into the plates 89 and 90. The holder 40, containing the buffing compound 39, is inserted between the plates by sliding the base 81 into the appropriate set of channels 91 until the inclined sidewall 92 is in contact with a rod 93, which is welded or otherwise secured to the base 81. Figures 6, 8, and 9 show the condition where the holder 40 is inserted in the lowermost set of notches 91. The holder 40 is locked in position by means of a locking screw 94 which threads into the notch 82 in the base 81. The holder 40 will be inserted in the lowermost set of notches while the buffing wheel has its maximum diameter, i. e., before an appreciable amount has been worn from the surface of the buffing wheel 37 by extended buffing operations.

When the block of buffing compound has worn down to a point where it is no longer usable, the holder 40 is released by threading back the screw 94 and a fresh block of compound in another holder is moved into the middle set of channels, a condition illustrated in Figure 7. As there shown, the use of the first block of buffing compound over a number of cycles of buffing operation sufficient to completely use up the first block of compound results in a reduction of the periphery of the buffing wheel 37 from the original periphery represented by the dotted-line to that shown by the solid line. Thus, by inserting a new block of compound in the middle series of channels 91, compensation is made for the wear on the buffing wheel occurring during the use of the previous block of compound. As will be noted from Figure 9, the line through the row of staggered adjusting screws 94, 95 and 96 is parallel to the inclined face 92 of the plate 90. Thus, the notch 82 is in alignment with the second locking screw 95 when the holder 40 is placed in the second series of channels.

After the use of the second block of compound,

the holder is again removed and a new block of compound inserted into the uppermost set of channels 91. The notch 82 is then in alignment with the adjusting screw 96 and the holder may be held between the plates 89 and 90 by the adjustment of the locking screw 96.

Upon the completion of the use of three separate blocks of buffing compound, the buffing wheel 37 is normally reduced to a diameter which is no longer usable. When this occurs, the buffing wheel 37 is replaced and the indexing mechanism realigned. This realignment is accomplished by turning the operating handle 56 to move the sliding block 57 back and away from the ratchet wheel 55. The adjusting screw 79 is threaded back into the sleeve 80. The buffing wheel is then, brought into contact manually with the workpiece, the wheel is held against the workpiece at the desired amount of pressure, and the screw 79 is then threaded against the bar 78 to maintain the desired pressure.

To summarize the operation of the device, the assembly provides a buffing wheel movable into position to buff a fixed workpiece at one end of its movement and to contact a buffing compound at the other end of its movement. Means are provided for advancing the buffing compound toward the surface of the wheel operable when the wheel is out of contact with the buffing compound, so that the contacting surface of the solid buffing compound is returned to the same position in each cycle. At the same time, means are provided for incrementally extending the arc of movement of the wheel toward the fixed workpiece during each cycle of operation to compensate for shrinkage in the radius of the wheel due to wear.

It will be evident from the foregoing that I have here provided an apparatus for buffing operations in which the amount of buffing compound to be applied to the surface of the buffing wheel is carefully controlled and compensation is made for the wear of the buffing compound during each cycle of operation and also for the wear resulting to the surface of buffing wheel from contacting the workpiece.

I claim as my invention:

1. A buffing wheel assembly comprising a tiltable buffing wheel adapted to buff a workpiece at one end of its tilting movement, means for holding a buffing compound in contacting relation with the surface of said wheel when said wheel is at the other end of said tilting movement, means for advancing said holding means a predetermined distance towards said wheel operable when said wheel is out of contact with said buffing compound, and means for advancing said wheel towards said workpiece a predetermined distance before each buffing operation.

2. A buffing wheel assembly comprising a buffing wheel movable into position to buff a workpiece at one end of its movement, means for holding a buffing compound in contact with the surface of said wheel when said wheel is at the other end of said movement, means operable while said wheel is out of contact with said buffing compound for advancing said holding means a predetermined distance towards said wheel, and means automatically increasing the length of movement of said wheel towards said workpiece to compensate for shrinkage in the radius of said wheel due to wear.

3. A buffing wheel assembly comprising a tiltable frame, a buffing wheel carried by said frame adapted to buff a workpiece at one end of its

tilting movement, an arm pivotally mounted about the tilting axis of said frame, means carried by said arm for holding a buffing compound in contact with the surface of said wheel when said wheel is at the other end of said tilting movement, means for advancing said holding means a predetermined amount towards said wheel operable while said wheel is out of contact with said buffing compound, and means for incrementally increasing the length of travel of said wheel towards said workpiece to compensate for the amount of surface worn from said wheel during each buffing operation.

4. A buffing wheel assembly comprising a tiltable frame, a buffing wheel assembly carried by said frame adapted to buff the surface of a workpiece at one end of its tilting movement, means for holding a buffing compound against the surface of said wheel at the other end of said tilting movement, means for advancing said holding means a predetermined amount towards said wheel operable when said wheel is out of contact with said buffing compound, and means cooperating with said advancing means to extend the arc of said tilting movement between successive buffing operations to compensate for the amount of surface worn from said wheel during each buffing operation.

5. A buffing wheel assembly comprising a tiltable frame, a buffing wheel carried by said frame adapted to buff the surface of a workpiece at one end of its tilting movement, an adjustable limiting means for limiting the extent of tilting movement, means for holding a buffing compound against the surface of said wheel at the other end of its tilting movement, means for advancing said holding means a predetermined amount toward the buffing wheel operable when said buffing wheel is out of contact with said buffing compound, and means for extending the arc of displacement of said frame operable after each buffing operation to compensate for wear on said wheel during each buffing operation.

6. In a buffing wheel assembly having a buffing wheel adapted to alternately buff a workpiece and contact a buffing compound, indexing means for advancing said buffing compound a predetermined amount towards said wheel after each buffing operation comprising a holder for said buffing compound, an arm extending from said holder, a lever pivotally mounted to said arm, a threaded shaft, a block in threaded engagement with said shaft and movable therealong, said block being pivotally connected to the other end of said lever, and pawl and ratchet means for periodically rotating said shaft to thereby cause displacement of said lever, said arm, and said holder a predetermined distance towards said buffing wheel.

7. In a buffing assembly having a rotatable buffing wheel adapted to periodically contact a block of solid buffing compound, means for holding said compound in contact with the surface of said wheel comprising an arm, a pair of upstanding plates secured to said arm, said plates having channels along the surface thereof, a base portion, spaced opposed walls, and a backing member defining a trough for receiving said compound, said base member being slidable within an opposed pair of said channels, and capable of being locked in a predetermined position between said plates.

8. In combination, a buffing wheel tiltable about an axis other than the axis of said wheel and an indexing mechanism for advancing a buffing compound a predetermined amount to

ward said tiltable buffing wheel, said mechanism comprising a holder for said compound, an arm extending from said holder pivotally mounted about said axis of tilting movement, a lever pivotally secured to one end of said arm for advancing the arm and holder to said wheel, and means actuated by the tilting movement of said assembly for moving said lever and thereby said arm and holder a predetermined distance toward said wheel during the tilting movement thereon.

9. A buffing assembly including a buffing wheel with a periphery positioned for contacting a workpiece, means for moving the buffing wheel through an arcuate path into engagement with the work, said means being operable to move said wheel out of contact with the work and into contact with a buffing compound such that a predetermined amount of buffing compound is applied to said wheel, and means for contemporaneously advancing the compound toward the wheel during each cycle of movement of said buffing wheel to compensate for the use of said compound.

10. A buffing assembly comprising a buffing wheel with a periphery positioned for contacting a workpiece, means for moving the buffing wheel into engagement with the work and operable to move the buffing wheel out of contact with the work and into contact with a buffing compound such that a predetermined amount of buffing

compound is applied to said wheel, advancing means for moving the compound toward the wheel, and compensating means for adjusting the movement of the wheel to compensate for the extent of surface removed from said wheel during each buffing operation, said advancing means and said compensating means being operable during each cycle of motion of said buffing wheel.
